United States Patent Office

Des. 189,000
Patented Oct. 11, 1960

189,000

FASTENER TOOL

Eugene O. Clay, Los Angeles, Calif., assignor to
North American Aviation, Inc.

Filed Oct. 16, 1959, Ser. No. 57,958

Term of patent 14 years

(Cl. D54—14)

Fig. 1 is a side elevational view of a fastener tool, showing my new design;

Fig. 2 is a top plan view thereof;

Fig. 3 is a front elevational view thereof;

Fig. 4 is a rear elevational view thereof;

Fig. 5 is a perspective view thereof.

I claim:

The ornamental design for a fastener tool, substantially as shown.
